(57) **CLAIM**

The ornamental design for an ozone generator, as shown and described.

DESCRIPTION

FIG. 1 is a perspective view of my new ozone generator taken from a point above and to one side of my new ozone generator.

FIG. 2 is a perspective view of my new ozone generator taken from an opposite side to that of FIG. 1.

FIG. 3 is an elevational end view of my new ozone generator; and,

FIG. 4 is an elevational bottom view of my new ozone generator.

The broken line showing of environmental structure in FIGS. 1-4 is for illustrative purposes only and forms no part of the claimed design.
